(57) **CLAIM**

The ornamental design for a wireless network device, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a top, front, right side perspective view of a first embodiment of a wireless network device showing our new design;

FIG. 2 is a bottom, back, left side perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a top, front, right side perspective view of a second embodiment of a wireless network device showing our new design;

FIG. 10 is a bottom, back, left side perspective view thereof;

FIG. 11 is a front view thereof;

FIG. 12 is a back view thereof;

FIG. 13 is a right side view thereof;

FIG. 14 is a left side view thereof;

FIG. 15 is a top view thereof;

FIG. 16 is a bottom view thereof;

FIG. 17 is a top, front, right side perspective view of a third embodiment of a wireless network device showing our new design;

FIG. 18 is a bottom, back, left side perspective view thereof;

FIG. 19 is a front view thereof;

FIG. 20 is a back view thereof;

FIG. 21 is a left side view thereof, the right side view being a mirror image of the left side view;

FIG. 22 is a top view thereof; and,

FIG. 23 is a bottom view thereof.

The broken lines in the drawing figures are for the purpose of illustrating portions of the wireless network device that form no part of the claimed design.
